ULTRA-HIGH-FREQUENCY SIGNAL-TRANSLATING STAGE

Harold A. Wheeler, Great Neck, N. Y., assignor to Hazeltine Corporation, a corporation of Delaware

Original application October 29, 1938, Serial No. 237,665. Divided and this application June 7, 1939, Serial No. 277,862

14 Claims. (Cl. 179—171)

This invention relates generally to ultra-high-frequency signal-translating stages for operation at such high frequencies that the conductance of the input circuit of the stage is an appreciable factor in determining the response characteristic of the stage.

This application is a division of applicant's copending application, Serial No. 237,665, entitled "Tunable selector of uniform band width," filed October 29, 1938, now United States Patent No. 2,196,881, issued April 9, 1940.

The input conductance of conventional vacuum tubes utilized in ultra-high-frequency translating stages, such as ultra-high-frequency amplifiers, tends materially to reduce the response of the stage. At frequencies above 10 megacycles or thereabout, the input conductance of conventional vacuum tubes is appreciable, while at frequencies higher than 50 megacycles, the input conductance, rather than the inherent tube and circuit capacitance, becomes a limiting factor in the response of the stage. The reason for this condition is that the maximum impedance which can be developed across the input circuit of the stage at such ultra-high frequencies is limited by the input conductance of the tube.

Also, at ultra-high frequencies, the input capacitance of such a stage and the variation of input capacitance with variations of the transconductance of the vacuum tube utilized are both appreciable, thereby adding other limitations to the response characteristic of the system. While there have been proposed arrangements for reducing the input capacitance of a vacuum tube and for maintaining it substantially uniform with variations of the transconductance of the tube when utilized in such an ultra-high-frequency stage, such arrangements in themselves have not been effective to compensate for the conductance of the input circuit and some arrangements for stabilizing the input capacitance have even introduced appreciable additional conductance into the input circuit. It is, therefore, desirable to provide an arrangement which may be used in such systems for maintaining relatively constant input capacitance and which is effective to reduce to a low value the conductance of the input circuit of the stage.

It is an object of the present invention, therefore, to provide an improved ultra-high-frequency signal-translating stage which is not subject to the above-mentioned disadvantages of the arrangements of the prior art.

It is a further object of the invention to provide an improved ultra-high-frequency signal-

translating stage, the response of which is not substantially limited by the conductance of the input circuit of the vacuum tube included in the stage.

In accordance with the invention, an ultra-high-frequency signal-translating stage for operating over a wide band of frequencies comprises, a vacuum tube having a cathode, an anode, and a control electrode, an input circuit coupled to the cathode and the control electrode and tunable over the aforesaid band of frequencies, and an output circuit coupled to the anode and the cathode. The stage has incidental reaction to the input circuit tending to develop substantial positive conductance thereacross under normal operating conditions of the stage. The stage also includes an additional electrode in the vacuum tube between the control electrode and the anode, the stage having appreciable capacitance between the control electrode and the additional electrode, and means for minimizing the feedback from the output circuit to the input circuit of signal energy of the frequency to which the input circuit is tuned. There is also included in the signal-translating stage a circuit coupled to the additional electrode and the cathode including an inductance proportioned to render the additional electrode circuit inductively reactive over the band of operating frequencies of the input circuit, and means for applying a unidirectional positive potential to the additional electrode, the inductance being of such value with respect to the aforesaid capacitance as effectively to neutralize a substantial part of the aforesaid conductance of the input circuit over the aforesaid band of operating frequencies.

The novel features which are believed to be characteristic of the invention are set forth with particularity in the appended claims. The invention itself, however, both as to its organization and method of operation, together with other and further advantages thereof, will best be understood with reference to the following specification, taken in connection with the accompanying drawing in which Fig. 1 is a circuit diagram of a stage of ultra-high-frequency amplification incorporating the invention; and Fig. 2 is another embodiment of the invention comprising a modification of the circuit of Fig. 1.

The input conductance of conventional vacuum tubes comprises three components: (1) that due to the dielectric loss of the tube insulators and the tube base and the effect of the space charge in the region of the cathode; (2) that due to reaction from the anode-cathode cir-

cuit to the grid-cathode circuit through the grid-cathode capacitance of the tube and the self-inductance of the cathode lead, the latter being common to the input and output circuits; and (3) that due to reaction caused by the finite transit time of electrons through the tube. The component of input conductance (1) is usually small as compared with that due to feedback through the grid-cathode capacitance and the self-inductance of the cathode lead, and also is small as compared to that component of the input conductance dependent on the transit time of electrons through the tube.

The magnitude of the component of input conductance of a conventional vacuum tube due to the transit time of electrons through the tube has been derived mathematically by D. O. North (see Proceedings of the Institute of Radio Engineers, vol. 24, No. 1, January 1936, page 108 et seq.). A mechanical explanation of the effect of transit time of electrons on the input conductance of a vacuum tube has been developed by W. R. Ferris (see Proceedings of the Institute of Radio Engineers, vol. 24, No. 1, January 1936, page 82 et seq.). These authors have shown that the component of input conductance G_t of conventional vacuum tubes dependent on the transit time of electrons through the tube is:

$$G_t = F \omega^2 gm \quad (1)$$

where:

F is a function of the transit time;
 ω is the mean angular frequency of the signal translated by the stage; and
 gm is the transconductance of the tube.

The factor F is dependent only slightly on variations of the transconductance gm and, for present purposes, may be considered to be a constant.

The conductance component G_L , due to feedback from the cathode circuit of the tube through the grid-cathode capacitance of the tube and the self-inductance of the cathode lead, may be shown to be:

$$G_L = \omega^2 C_{gc} L_c gm \quad (2)$$

where:

C_{gc} is the interelectrode capacitance between the control grid and the cathode of the tube; and

L_c is the inductance of the cathode lead common to both the input and output circuits of the tube.

The total input conductance due to reaction to the input circuit of such a high-frequency stage, neglecting that component due to dielectric losses, may, therefore, be expressed as:

$$G = \omega^2 C_{gc} L' c gm \quad (3)$$

where $L' c$ is a simulated cathode-lead inductance that would account for the total input conductance of the tube solely on the basis of feedback through the grid-cathode capacitance. It will be seen from Equation 3 that the positive conductance of the input circuit increases with frequency over the operating frequency range of the stage. The simulated cathode-lead conductance as determined from Equation 3 has the value:

$$L' c = \frac{G}{\omega^2 C_{gc} gm} \quad (4)$$

Such an ultra-high-frequency stage of amplification is shown in the circuit of Fig. 1 in which reference numerals correspond to those identifying the same circuit elements in the above-mentioned copending application. This ultra-high-

frequency signal-translating stage is adapted to operate over a wide band of frequencies and comprises a vacuum-tube amplifier 11 having an input circuit including an adjustable inductor 31 tuned by capacitance 36, shown in dotted lines for the reason that it may be comprised in whole or in part of the inherent capacitance of the circuit of the control electrode or grid of tube 11, coupled to the control grid and cathode of tube 11 and tunable over the operating band of frequencies. A grid-leak resistor 38 is provided for tube 11, by-passed for high-frequency currents by a condenser 37. The output circuit of the stage includes a tuned circuit comprising a condenser 14 and an inductance 15 coupled to the anode and cathode of tube 11. The amplifier stage thus far described has incidental reaction to the input circuit 31, 36 tending to develop substantial positive conductance thereacross under normal operating conditions. In accordance with the invention, an additional electrode 16 is provided in vacuum tube 11 between the control grid and the anode of the tube. The amplifier stage includes a circuit coupled to the additional electrode 16 and the cathode including elements of fixed values providing inductive reactance which increases with frequency over the operating frequency band of the stage comprising an inductance 42 proportioned to render the additional electrode circuit inductively reactive over the band of operating frequencies of the input circuit 31, 36. There is also provided means for applying a unidirectional positive potential to the additional electrode 16 comprising a unidirectional source 17 included in series with the inductance 42 in the additional electrode-cathode circuit. A capacitance 44 is effectively coupled between the control grid of tube 11 and the additional electrode 16 and is shown in dotted lines for the reason that it may be comprised in whole or in part of interelectrode capacitance within the tube.

In considering the operation of the circuit of Fig. 1, it will be seen that negative conductance is introduced into the input circuit of the high-frequency stage shown, due to the voltage developed across inductance 42 and fed back to the input circuit through capacitance 44. This negative conductance $-G_g$ varies in accordance with the expression:

$$-G_g \alpha \omega^2 C_{gs} L_s \text{ or } -G_g = \omega^2 C_{gs} L_s g m' \quad (5)$$

where:

C_{gs} is the value of capacitance 44;

L_s is the value of inductance 42; and

$g m'$ is the value of positive transconductance from grid to auxiliary electrode 16.

In accordance with the invention, therefore, the positive conductance of the input circuit represented by Equation 3 is wholly or partially neutralized by the negative conductance effect of the added inductance 42, as given by expression (5). In order to produce exact neutralization, the positive conductance of Equation 3 is made to be equal to the negative conductance of expression (5). That is:

$$\omega^2 C_{gc} L' c g m = \omega^2 C_{gs} L_s g m' \quad (6)$$

or

$$L_s = \frac{C_{gc} L' c g m}{C_{gs} g m'} \quad (7)$$

Therefore, it is seen that the invention may be utilized simply by connecting an inductance L_s in the screen-grid circuit of a conventional vacuum tube, the value of inductance being de-

terminated in accordance with Equation 7 above. From Equation 7 it will be seen that the inductance L_s is so proportioned with respect to the simulated inductance L'_s that the voltage developed across the inductance L_s and coupled to the input circuit 31, 36 through the capacitance 44 effectively neutralizes a substantial part of the positive conductance in the input circuit over the band of operating frequencies. In practice, however, it may be more convenient to place an adjustable inductance in the circuit in place of inductance 42 in order that its inductance may be adjusted to determine the exact inductance required for neutralization.

In the foregoing described operation of the Fig. 1 embodiment of the invention, the feed-back conductance component in the input circuit, which is produced by the feed-back through the anode-to-control-grid capacitance of tube 11 of the signal developed across the tuned output circuit 14, 15 has been ignored on the assumption that this component of conductance is negligible in comparison to that produced by the auxiliary electrode 16. This analysis and assumption is correct where the output circuit 14, 15 is tuned to an operating frequency considerably different from that of the input tuned circuit 31, 36, as in the arrangement of Fig. 9 of the aforementioned Wheeler patent where the output circuit of the amplifier 11 is tuned to a relatively low intermediate frequency and the input circuit is tuned to the relatively high frequency of a received carrier signal. In this event, the output tuned circuit 14, 15 of the present arrangement has relatively low impedance at the frequency of the input signal and consequently little or no signal voltage of this frequency is developed across the output circuit and is fed back to the control grid through the anode-to-control-grid capacitance. Consequently, the component of conductance due to the anode-to-control-grid capacitance is negligible and may be ignored. This is also true in the case where the output tuned circuit 14, 15 is tuned to the same operating frequency as the input tuned circuit 31, 36, but is heavily damped as required in a wide-band amplifier.

Where it is necessary that the output tuned circuit 14, 15 be resonant with the input tuned circuit 31, 36 at the same operating frequency and have high selectivity, an appreciable signal voltage is then developed across the output tuned circuit. The component of the conductance due to the feedback of this voltage through the anode-to-control-grid capacitance detrimentally affects the desired balance of positive and negative conductances over the wide range of operating frequencies of the stage unless the effective anode-to-control-grid capacitance is reduced to a small value by interelectrode shielding means. In accordance with one feature of the invention, therefore, the detrimental effect of an appreciable value of anode-to-control-grid capacitance, which would tend to impair the desired operation if the input and output circuits of the amplifier were tuned together to any given operating frequency in the wide frequency band, is reduced by the provision in tube 11 of certain electrodes, for example, a suppressor grid as shown in the Fig. 1 arrangement, and the suppressor and screen grids of Fig. 2 presently to be considered.

The suppressor grid of the circuit of Fig. 1 also greatly reduces the coupling between the auxiliary electrode 16 and the output anode.

However, it will be seen that the potential of auxiliary electrode 16 varies somewhat at signal frequencies so that it no longer completely fulfills the usual function of a screen-grid electrode in a vacuum tube. For this reason, it may be desirable to include an additional electrode, which has the usual functions of a screen grid, between the auxiliary electrode 16 and the anode of vacuum tube 11. This arrangement is shown in Fig. 2 in which the additional screen electrode is represented at 18. The circuit of Fig. 2 is otherwise identical to that of Fig. 1 and it is believed that the operation of the circuit of Fig. 2 will be readily understood from the description given above with reference to the operation of Fig. 1.

From the above description of the invention, it will be seen that the inductance 42 is of such value with respect to the capacitance 44 between the additional electrode 16 and the control grid of tube 11 as effectively to neutralize a substantial part of the positive conductance of the input circuit 31, 36 over the band of operating frequencies.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. An ultra-high-frequency signal-translating stage for operating over a wide band of frequencies comprising, a vacuum tube having a cathode, an anode, and a control electrode, an input circuit coupled to said cathode and said control electrode and tunable over said band of frequencies, an output circuit coupled to said anode and said cathode, said stage having incidental reaction to said input circuit tending to develop substantial positive conductance thereacross under normal operating conditions, an additional electrode in said vacuum tube between said control electrode and said anode, said stage having appreciable capacitance between said control electrode and said additional electrode, means for minimizing the feedback from said output circuit to said input circuit of signal energy of the frequency to which said input circuit is tuned, a circuit coupled to said additional electrode and said cathode including inductance proportioned to render said additional electrode circuit inductively reactive over said range of operating frequencies of said input circuit, and means for applying a unidirectional positive potential to said additional electrode, said inductance being of such value with respect to said capacitance as effectively to neutralize a substantial part of said conductance of said input circuit over said band of operating frequencies.

2. An ultra-high-frequency signal-translating stage for operating over a wide band of frequencies comprising, a vacuum tube having a cathode, an anode, and a control electrode, an input circuit coupled to said cathode and said control electrode and tunable over said band of frequencies, an output circuit coupled to said anode and said cathode, said stage having incidental reaction to said input circuit tending to develop substantial positive conductance thereacross under normal operating conditions of said stage, an additional electrode in said vacuum tube between

said control electrode and said anode, said stage having appreciable capacitance consisting of only interelectrode capacitance between said control electrode and said additional electrode, means for minimizing the feedback from said output circuit to said input circuit of signal energy of the frequency to which said input circuit is tuned, a circuit coupled to said additional electrode and said cathode and including inductance proportioned to render said additional electrode circuit inductively reactive over said range of operating frequencies of said input circuit, and means for applying a unidirectional positive potential to said auxiliary electrode, said inductance being of such value with respect to said capacitance as effectively to neutralize a substantial part of said conductance of said input circuit over said band of operating frequencies.

3. An ultra-high-frequency signal-translating stage for operating over a wide band of frequencies comprising, a vacuum tube having a cathode, an anode, and a control electrode, an input tuned circuit coupled to said cathode and said control electrode and tunable over said band of frequencies, an output tuned circuit coupled to said anode and said cathode, said stage having incidental reaction to said input circuit tending to develop substantial positive conductance thereacross under normal operating conditions of said stage, an additional electrode in said vacuum tube between said control electrode and said anode, said stage having appreciable capacitance between said control electrode and said additional electrode, means for minimizing the feedback from said output circuit to said input circuit of signal energy of the frequency to which said input circuit is tuned, a circuit coupled to said additional electrode and said cathode and including inductance proportioned to render said additional electrode circuit inductively reactive over said range of operating frequencies of said input circuit, and means for applying a unidirectional positive potential to said auxiliary electrode, said inductance being of such value with respect to said capacitance as effectively to neutralize a substantial part of said conductance of said input circuit over said band of operating frequencies.

4. An ultra-high-frequency signal-translating stage for operating over a wide band of frequencies comprising, a vacuum tube having a cathode, an anode, and a control electrode, an input circuit coupled to said cathode and said control electrode and tunable over said band of frequencies, an output circuit coupled to said anode and said cathode, said stage having incidental reaction to said input circuit tending to develop substantial positive conductance thereacross under normal operating conditions of said stage, an additional electrode in said vacuum tube between said control electrode and said anode, said stage having appreciable capacitance between said control electrode and said additional electrode, a circuit coupled to said additional electrode and said cathode and including inductance proportioned to render said additional electrode circuit inductively reactive over said range of operating frequencies of said input circuit, a screen electrode between said additional electrode and said anode for minimizing the feedback from said output circuit to said input circuit of signal energy of the frequency to which said input circuit is tuned, and means for applying a unidirectional positive potential to said additional electrode, said inductance be-

ing of such value with respect to said capacitance as to neutralize a substantial part of said conductance of said input circuit over said band of operating frequencies.

5. An ultra-high-frequency signal-translating stage for operating over a wide band of frequencies comprising, a vacuum tube having a cathode, an anode, and a control electrode, an input circuit coupled to said cathode and said control electrode and tunable over said band of frequencies, an output circuit coupled to said anode and said cathode, said stage having incidental reaction to said input circuit tending to develop substantial positive conductance thereacross under normal operating conditions of said stage, an additional electrode in said vacuum tube between said control electrode and said anode, said stage having appreciable capacitance between said control electrode and said additional electrode, a suppressor electrode between said additional electrode and said anode for minimizing the feedback from said output circuit to said input circuit of signal energy of the frequency to which said input circuit is tuned, a circuit coupled to said additional electrode and said cathode and including inductance proportioned to render said additional electrode circuit inductively reactive over said range of operating frequencies of said input circuit, and means for applying a positive potential to said additional electrode, said inductance being of such value with respect to said capacitance as to neutralize a substantial part of said conductance of said input circuit over said band of operating frequencies.

6. An ultra-high-frequency signal-translating stage for operating over a wide band of frequencies comprising, a vacuum tube having a cathode, an anode, and a control electrode, an input circuit coupled to said cathode and said control electrode and tunable over said band of frequencies, an output circuit coupled to said anode and said cathode and including a portion common to said input circuit, said stage having incidental reaction to said input circuit tending to develop substantial positive conductance thereacross under normal operating conditions of said stage which is effectively simulated by an inductance in said common portion of said input and output circuits, an additional electrode in said vacuum tube between said control electrode and said anode, said stage having appreciable capacitance between said control electrode and said additional electrode, means for minimizing the feedback from said output circuit to said input circuit of signal energy of the frequency to which said input circuit is tuned, a circuit coupled to said additional electrode and said cathode and including inductance proportioned to render said additional electrode circuit inductively reactive over said range of operating frequencies of said input circuit, and means for applying a unidirectional positive potential to said additional electrode, said additional electrode circuit inductance being so proportioned with respect to said simulated inductance that the voltage developed across said additional electrode circuit inductance and coupled to said input circuit through said capacitance effectively neutralizes a substantial part of said conductance in said input circuit over said band of operating frequencies.

7. An ultra-high-frequency signal-translating stage comprising, a vacuum tube having a cathode, an anode, and a control electrode, an input

circuit coupled to said cathode and said control electrode, an output circuit coupled to said anode and said cathode, said stage comprising incidental reaction to said input circuit tending to develop substantial positive conductance G_g thereacross under normal operating conditions of said stage, an additional electrode in said vacuum tube between said control electrode and said anode, said stage having appreciable capacitance C_{gs} between said control electrode and said additional electrode, a circuit coupled to said additional electrode and said cathode and including inductance having a value L_s proportioned to render said additional electrode circuit inductively reactive at the operating frequency of said stage, and means for applying a unidirectional positive potential to said additional electrode, said inductance and capacitance being proportioned in accordance with the expression

$$G_g = -gm' \omega^2 C_{gs} L_s$$

where ω is the mean frequency of the signal input to said stage and gm' the value of transconductance between said control electrode and said additional electrode.

8. An ultra-high-frequency signal-translating stage comprising, a vacuum tube having a cathode, an anode, and a control electrode, an input circuit coupled to said cathode and said control electrode, an output circuit coupled to said anode and said cathode, said stage comprising an interelectrode capacitance C_{ee} between said control electrode and said cathode and having an incidental reaction to said input circuit tending to develop substantial positive conductance G_g thereacross under normal operating conditions of said stage, an additional electrode in said vacuum tube between said control electrode and said anode, said stage having appreciable capacitance C_{gs} between said control electrode and said additional electrode, a circuit coupled to said additional electrode and said cathode and including inductance having a value L_s proportioned to render said additional electrode circuit inductively reactive at the operating frequency of said stage, and means for applying a positive unidirectional potential to said additional electrode, said inductance and capacitance being proportioned in accordance with the expression.

$$L_s = \frac{gm' C_{ee} L'_c}{C_{gs} g m'}$$

where the parameters have the significance given in the specification.

9. An ultra-high-frequency signal-translating stage for operating over a wide band of frequencies comprising, a vacuum tube having a cathode, an anode, and a control electrode, an input circuit coupled to said cathode and said control electrode and tunable over said band of frequencies, an output circuit coupled to said anode and said cathode, said stage having incidental reaction to said input circuit tending to develop substantial positive conductance thereacross under normal operating conditions, an additional electrode in said vacuum tube, said control electrode having positive transconductance with respect to said additional electrode, said stage having appreciable capacitance between said control electrode and said additional electrode, means for minimizing the feedback from said output circuit to said input circuit of signal energy of the frequency to which said input circuit is tuned, a circuit coupled to said

additional electrode and said cathode including inductance proportioned to render said additional electrode circuit inductively reactive over said range of operating frequencies of said input circuit, and means for applying a unidirectional positive potential to said additional electrode, said inductance being of such value with respect to said capacitance as effectively to neutralize a substantial part of said conductance of said input circuit over said band of operating frequencies.

10. An ultra-high-frequency signal-translating stage for operating over a wide band of frequencies comprising, a vacuum tube having a cathode, an anode, and a control electrode, an input circuit coupled to said cathode and said control electrode and tunable over said band of frequencies, an output circuit coupled to said anode and said cathode and including a portion common to said input circuit, said stage having incidental reaction to said input circuit tending to develop substantial positive conductance thereacross under normal operating conditions of said stage which is effectively simulated by an inductance in said common portion of said input and output circuits, an additional electrode in said vacuum tube, said control electrode having positive transconductance with respect to said additional electrode, said stage having appreciable capacitance between said control electrode and said additional electrode, means for minimizing the feedback from said output circuit to said input circuit of signal energy of the frequency to which said input circuit is tuned, a circuit coupled to said additional electrode and said cathode and including inductance proportioned to render said additional electrode circuit inductively reactive over said range of operating frequencies of said input circuit, and means for applying a unidirectional positive potential to said additional electrode, said additional electrode circuit inductance being so proportioned with respect to said simulated inductance that the voltage developed across said additional electrode circuit inductance and coupled to said input circuit through said capacitance effectively neutralizes a substantial part of said conductance in said input circuit over said band of operating frequencies.
11. An ultra-high-frequency signal-translating stage comprising, a vacuum tube having a cathode, an anode, and a control electrode, an input circuit coupled to said cathode and said control electrode, an output circuit coupled to said anode and said cathode, said stage comprising incidental reaction to said input circuit tending to develop substantial positive conductance G_g thereacross under normal operating conditions of said stage, an additional electrode in said vacuum tube, said control electrode having positive transconductance with respect to said additional electrode, said stage having appreciable capacitance C_{gs} between said control electrode and said additional electrode, a circuit coupled to said additional electrode and said cathode and including inductance having a value L_s proportioned to render said additional electrode circuit inductively reactive at the operating frequency of said stage, and means for applying a unidirectional positive potential to said additional electrode, said inductance and capacitance being proportioned in accordance with the expression

$$G_g = -gm' \omega^2 C_{gs} L_s$$

where ω is the mean frequency of the signal input to said stage and gm' the value of transconductance between said control electrode and said additional electrode.

12. An ultra-high-frequency signal-translating stage comprising, a vacuum tube having a cathode, an anode, and a control electrode, an input circuit coupled to said cathode and said control electrode, an output circuit coupled to said anode and said cathode, said stage comprising an interelectrode capacitance C_{sc} between said control electrode and said cathode and having an incidental reaction to said input circuit tending to develop substantial positive conductance G_g thereacross under normal operating conditions of said stage, an additional electrode in said vacuum tube, said control electrode having positive transconductance with respect to said additional electrode, said stage having appreciable capacitance C_{as} between said control electrode and said additional electrode, a circuit coupled to said additional electrode and said cathode and including inductance having a value L_s proportioned to render said additional electrode circuit inductively reactive at the operating frequency of said stage, and means for applying a positive unidirectional potential to said additional electrode, said inductance and capacitance being proportioned in accordance with the expression

$$L_s = \frac{gmC_{sc}L'}{C_{as}gm'}$$

where the parameters have the significance given in the specification.

13. An ultra-high-frequency signal-translating stage for operating over a wide band of frequencies comprising, a vacuum tube having a cathode, an anode, and a control electrode, an input circuit coupled to said cathode and said control electrode, an output circuit coupled to said anode and said cathode, said stage having incidental reaction to said input circuit tending

to develop thereacross substantial positive conductance which increases with frequency over the operating range of said stage, an additional electrode in said vacuum tube, said control electrode having positive transconductance and appreciable capacitance with respect to said additional electrode, a circuit included between said additional electrode and said cathode comprising elements of fixed values providing inductive reactance which increases with frequency over said operating frequency range, said inductive reactance being of such value with respect to said capacitance as effectively to neutralize a substantial part of said conductance over said operating range.

14. An ultra-high-frequency signal-translating stage for operating over a wide band of frequencies comprising, a vacuum tube having a cathode, an anode, and a control electrode, an input circuit coupled to said anode and said cathode and including a portion common to said input circuit, said stage having incidental reaction to said input circuit tending to develop thereacross substantial positive conductance which increases with frequency over the operating range of said stage and which is effectively simulated by an inductance in said common portion of said input and output circuits, an additional electrode in said vacuum tube, said control electrode having positive transconductance and appreciable capacitance with respect to said additional electrode, a circuit included between said additional electrode and said cathode comprising elements of fixed values providing inductive reactance which increases with frequency over said range, said inductive reactance being so proportioned with respect to said simulated inductance that the voltage across said elements and coupled to said input circuit through said capacitance effectively neutralizes a substantial part of said conductance in said input circuit over said operating range.

HAROLD A. WHEELER.
